(57) **CLAIM**

The ornamental design for an electronic guestbook console, as shown and described.

DESCRIPTION

FIG. 1 is a front-left and top perspective view of an electronic guestbook console having an accessory drawer shown in a closed position and with an electronic guestbook being omitted to more clearly depict what is claimed;

FIG. 2 is a front-right and top perspective view of the console of FIG. 1;

FIG. 3 is a front-left and top perspective view of the console of FIG. 1, with the accessory drawer shown in an open position;

FIG. 4 is a front elevation view of the console of FIG. 1;

FIG. 5 is a rear elevation view of the console of FIG. 1;

FIG. 6 is rear and top perspective view of an upper portion of the console of FIG. 1, with the lower console portion and camera enclosure being omitted to more clearly depict what is claimed;

FIG. 7 is a top plan view of the console of FIG. 1;

FIG. 8 is a bottom plan view of the console of FIG. 1 with the accessory drawer shown in an open position;

FIG. 9 is a left elevation view of the console of FIG. 1; and, FIG. 10 is a right elevation view of the console of FIG. 1.

The broken lines shown in the figures, including those of a console base, camera enclosure, console pedestal legs and keyboard, illustrate the environment only and form no part of the claimed design. The dash-dot-dash broken lines shown adjacent the shade lines on the accessory drawer in FIGS. 3 and 8 define the boundaries of the claimed design and form no part of the claimed design.
